UNITED STATES PATENT OFFICE.

JOSEF PABST, OF ZURICH, SWITZERLAND.

CLOTH HOLDER.

Application filed January 19, 1921. Serial No. 438,500.

To all whom it may concern:

Be it known that I, JOSEF PABST, a citizen of the Republic of Switzerland, residing at Zurich, in the Canton of Zurich, Switzerland, have invented certain new and useful Improvements in Cloth-Holders, of which the following is a specification.

There are clasps or cloth-holders which are constructed of a lower and a cover part 10 in the form of frames whereby the cover part when in closed position is partially overlapped by the lower part. The present invention is for improvements in cloth-holders of the type mentioned and it consists of a novel device for connecting the said lower and cover parts. This device comprises a connecting link or plate, one end thereof being hinged to the cover part and the other end being pivotally connected 20 with a bridge-piece forming an integral member of the lower part and projecting upwardly of the main frame thereof. The pivot of the connecting link being thus arranged, and the said link allowing a slight 25 sliding movement of the lower and cover parts when in closed position, these parts cause the cloth or fabric to be tightly gripped without a possibility of such parts becoming accidentally unlocked.

Several forms of construction in which my invention may be embodied are illustrated in the accompanying drawings, in which:

Fig. 1 shows a plan view of a holder according to its first construction;

Fig. 2 is a section through line A—B in Fig. 1;

Fig. 3 shows a side view of Fig. 1 with the holder in closed position and as applied to some fabric;

Fig. 4 also represents a side view, but with the holder in open position, that is, before gripping the fabric;

Figs. 5 and 6 show modifications of a 45 detail;

Fig. 7 shows a plan view of a holder according to a second construction;

Fig. 8 illustrates an end view thereof;

Fig. 9 shows a side view of Fig. 7 with the 50 holder closed and applied to some fabric.

Fig. 10 shows a plan view of the combination of two cloth-holders, and

Fig. 11 is a side view of Fig. 10, the

holder being shown as applied to some fabric.

Similar parts are referred to by like letters or numerals throughout the views.

In the construction shown in Figs. 1 to 3, the reference 1 designates the lower, and 2 the cover part of the cloth-holder. Each 60 of these parts is made of wire and in the form of an oblong frame. The lower part is provided at one end with two eyelets 3 and upwardly extending thereof and connecting the same is a bridge-piece 4. This 65 bridge-piece 4 forms a rigid and integral member with the lower part 1 and projects upwardly of the plane of the main frame of such lower part. Hinged to the eyelets 3 is a clamping member 5 while the central 70 portion of the bridge-piece 4 has linked to it one end of a plate 6 the other end of the latter being linked to the corresponding end of the cover part 2. The plate or connecting link 6 is therefore capable of turning 75 about the horizontally disposed portion of the bridge-piece 4, the said horizontal portion serving thus as a pivot for the link 6, and being rigidly connected with the lower part 1 and lying above its plane. The lower 80 frame 1 is furthermore provided with two inwardly projecting bends 7 which abut against one another and thus form a laterally disposed bridge. The frame 2 is somewhat 85 smaller in width than the width of the inside of the frame 1 in order to allow of the projection through the latter of the free end 8 of the cover part in such a manner that the end 9 of the lower frame overlaps the end 8 of the said cover part. The 90 rear end 10 thereof, which is linked to the plate 6, is curved outwardly and the said free end is shouldered off at 11, Figs. 3 and 4.

If the cloth or fabric 12, for instance the upper end of stockings or socks, is placed 95 on the lower frame 1 in the manner shown in Fig. 4, and assuming the cover frame to be swung in the direction of the arrow indicated in such figure in order to take the position according to Fig. 3, the fabric 12 100 will be gripped by and pressed between the bottom and cover frame. The fabric is hereby made to follow the undulating form of the cover frame and any superfluous material or folds 13 of the fabric may be 105 tucked away beneath the curved portion 10.

In this position, namely the locking position, the connecting link 6 is downwardly directed (Fig. 3) and its lower hinge-portion lies above the upper face of the lower 5 part and does not, therefore, project below the same. If now a pull is exerted at 12 on the cloth (Fig. 3) or fabric, the latter, upon a pressure on the end 8 of the cover 10 part lying approximately parallel to the lower part, may cause a slight sliding movement of the cover part, the result being a tight clamping of the fabric between the portions 7 and 11. Inasmuch as the link 6 is pivotally mounted on an axle which is 15 rigid and integral with the lower part and situated above the plane thereof, the slight sliding movement is unable to cause the unlocking of the cloth-holder. If the cover 20 part 2 is swung in a direction opposite to that of the arrow in Fig. 4, a portion of the lower part 2 is made to lie on the pivot of the link 6, the part 2 thus representing a double-armed lever of which the end 9, by a pressure of the thumb on the shorter arm 25 located behind the bridge-piece 4, may be moved away from the end 8 in order more easily to open the cloth-holder and insert the fabric. This form of construction is 30 particularly suitable as a suspender for ladies' stockings in which case provision may also be made on the clamping member 5 of a band or strap adapted to be attached, for instance, to the corset.

As illustrated in Fig. 5, the clamping 35 member 5^a may be formed with an extension 14 which device is especially convenient when the cloth-holder is intended for use with men's socks. In such case the holder, by means of the said extension, may easily 40 be secured to the pants. By way of alternative and as shown in Fig. 6, the clamping member 5^b may also be fashioned into a suspension hook 15.

Referring to the construction of holder 45 shown in Figs. 7 to 9, the lower frame 1^a is provided at either side with oppositely disposed integral shoulders 17 projecting inwardly of the frame, while the middle portion of the sides of the cover part is bent 50 downwardly at 18 whereas the adjacent portions of the said bend 18, designated by 19 and 20 respectively, are curved upwardly, the curves 20 moreover being obliquely arranged in relation to the sides of the frames. 55 In this way the fabric is firmly gripped by a series of undulating members of the cover part. The lower frame 1^a forms an integral part with the clamping member 5^c and is constructed of a single piece of wire of 60 which the two ends are fashioned into eyelets 3^a engaging with the vertically disposed members 4^a of the bridge-piece of the clamping member.

In the last construction illustrated in 65 Figs. 10 and 11, the two combined lower

frames 1^d and 1^e are linked to each other by a ring 23 and eyelets 3^b and 3^c formed, respectively, on the neighboring ends of the said lower frames. This form of construction combining two holders enables the 70 fabric 12^d of pants or a hose to be secured by the aid of one of the holders, at the same time rendering it possible similarly to secure the end 12^e of stockings or socks. Here too, the portions 2^d and 2^e of the cover 75 frames are overlapped by the corresponding parts of the lower frames thus being adapted to grip the fabric placed between the pairs of frames very firmly. In this 80 modification the members of the cover frame adjacent to the eyelets 3^b and 3^c, instead of being upwardly curved, are straight.

Having now fully described my said invention what I claim and desire to secure by Letters Patent is:—

1. In a cloth-holder, the combination, of a lower and a cover part the lower part in the form of an oblong frame, the said lower part at one end being formed with an integral bridge-piece which projects upwardly of the plane of the lower frame and the cover part when in closed position being partially overlapped by the lower part, and a connecting link of which one end is hinged to the cover part and the other end pivotally connected with the aforesaid bridge-piece. 95

2. In a cloth-holder, the combination, of a lower and a cover part the lower part in the form of an oblong frame, the said lower part at one end being formed with an integral bridge-piece which projects upwardly of the plane of the lower frame and the cover part when in closed position being partially overlapped by the lower part, and a connecting link of which one end is hinged to the cover part and the other end pivotally connected with the bridge-piece, the said link in closed position extending downwardly at 100 an angle to the plane of the lower frame and its lower hinge-portion lying above the upper face of the said lower frame. 105

3. In a cloth-holder, the combination, of a lower part in the form of an oblong frame constructed of a single wire bent at one end and at each side thereof into an eyelet, the wire at the side of said eyelets projecting upwardly of the plane of the oblong frame and forming with the eyelets a bridge-piece, a connecting link hinged at one end to the bridge-piece, and a cover part in the shape 115 of an oblong frame made of a single wire hinged to the other end of the said connecting link. 120

4. In a cloth-holder, the combination, with a lower part in the form of an oblong wire frame having at one end and between the sides thereof at least one bend extending towards the centre of the frame, of a cover part in the shape of an oblong wire frame provided between its two ends with 125 130

at least one bend which in closed position lies opposite and near the first bend, and a link connecting the lower and cover parts and at one end being pivoted to the lower 5 part at a point situated above the plane thereof.

In testimony whereof I have hereunto set

my hand in the presence of two subscribing witnesses.

JOSEF PABST.
